UNITED STATES PATENT OFFICE.

ANTHONIE W. REKENTHALER, OF DUNLO, PENNSYLVANIA.

CAN-OPENER.

1,276,693.

Specification of Letters Patent. Patented Aug. 20, 1918.

Application filed May 11, 1916. Serial No. 96,837.

To all whom it may concern:

Be it known that I, ANTHONIE W. REKENTHALER, a citizen of the United States, residing at Dunlo, in the county of Cambria and State of Pennsylvania, have invented certain new and useful Improvements in Can-Openers; and I do hereby declare the following to be a full, clear, and exact description of the same, when taken in connection with the accompanying drawings, forming part of this specification.

This invention relates to an improved can opener, and the primary object of the invention is to provide a simple, convenient, and highly efficient construction, which may be manufactured at a very low cost.

A special feature of the present improved construction lies in the provision of a guiding member adapted to lie on the outside of a can and to engage underneath the flange joining the top and side walls of the can. With a guiding member so arranged and constructed, a very powerful leverage may be exerted in manipulating the tool to cut the metal with the blade, without any danger of the tool slipping off the can. This construction obviates practically all danger of cutting the hand, when opening the can, and, at the same time, greatly increases the efficiency of the tool without materially adding to the cost of manufacture.

A full understanding of the invention will be attained from the ensuing detailed description when taken in connection with the accompanying drawings which illustrate a structural embodiment of the invention in a preferred form. The novel features of the invention will be particularly pointed out and specified in the claims at the end of the specification.

In the drawings:—

Figure 1 is a side elevation showing one form of can opener at the left hand end of the shank and a modified form at the right hand end of the shank.

Fig. 2 is an enlarged detailed view of the form illustrated at the left hand end of Fig. 1.

Fig. 3 is a vertical sectional elevation on the line 3—3 of Fig. 2.

Fig. 4 is a plan view of a blank showing the method of constructing the blade and the guiding member.

Fig. 5 is a perspective view showing the application of the can opener, illustrated in Fig. 2, to a can.

Fig. 6 is an enlarged detailed view of the form of can opener illustrated at the right hand end of Fig. 1.

Fig. 7 is a vertical sectional elevation on the line 7—7 of Fig. 6.

Like characters of reference in the several figures indicate the same parts.

In the embodiment of the invention illustrated more particularly in Figs. 2 to 5 inclusive, the shank A is provided with a blade B, the latter being spaced from the plane of the shank, and preferably lying approximately parallel thereto. The said shank A, in the present instance, consists of an elongated flat bar of suitable metal, and constitutes the handle of the tool, although any preferred form of handle grip may be provided, if desired. The blade B is sharpened along its front edge to form a cutting edge b, which is preferably arcuately shaped in the plane of the blade and inclined forwardly toward the top of the blade and with relation to the longitudinal axis of the shank A. If desired, the cutting edge b may be notched or serrated, as shown more particularly in Fig. 2. A convenient way of obtaining the proper inclination of the blade consists in bending the metal supporting the blade over the front face of the shank and at an acute angle to the longitudinal axis of the shank, the angle being sufficiently great to provide for a comparatively wide sweep when oscillating the tool up and down along the can in performing the cutting operation. The blade is designed to penetrate the metal of the top of a can along a line adjacent the flange joining the top of the can with the sides, and to cut the metal by a downward pressure on the handle or shank A, as indicated by the dotted lines of Fig. 5. This mode of operation is preferable to that now generally in use, because the downward stroke turns the edges of the metal at the cut inwardly instead of outwardly, and the danger of cutting the hand on the edges of the tin, in operating the tool to remove the cover of a can, is thereby reduced to a minimum degree. At its lower end the blade B is preferably pointed, as shown.

The blade B, in cutting the top off a can, is guided by the member C. This guiding member is adapted to lie against the side wall of the can and to engage underneath the flange joining the top and side walls of the can. The end of the guiding member in

engagement with the flange acts as a fulcrum about which the up and down movements of the blade are effected; the combined effect of the blade located between the edges of the cut formed in the top of the can and the guiding member in engagement with the flange, is to lock the tool in the can, while being operated. Thus danger of the tool slipping when in operation, is greatly reduced and by the improved tool of the present invention, cans may be opened with comparative safety. The guiding member C projects from the side of the shank A facing the blade B, and the front or engaging face c of said guiding member is positioned behind the rear face b' of the blade to permit the blade to clear the top edge of a can, when applying the tool, it being understood that the face c of the guiding member lies against the side wall of the can, as illustrated in Fig. 5 of the drawing. It will be noted that the guiding member is positioned on the shank A forwardly of the blade B, and the rear edge c' of said member inclines toward the top in the same general direction as the cutting edge b of the blade. This arrangement provides the necessary clearance, for the movement of the blade in cutting the top off a can. The main lower portion of the front edge c² of the guiding member is flush with the front edge a' of the shank, but the extreme upper end of the guiding member projects beyond the said edge a', as shown at c³ in Fig. 2. Said projection c³ is bounded in the rear by the inclined rear edge c' of the guiding member, and the top of the projection c³ is below the inner portion of the angular bend b² of the blade. By projecting the upper end of the guiding member beyond the front edge of the shank, it is possible to position the blade quite close to the front of said shank, and a very great freedom of movement of the tool is permitted.

The operation of the tool will be readily understood by an inspection of Fig. 5 of the drawing. As shown therein, the tool is applied by slipping it over the top edge of a can, the lower end of the blade B being pushed into the metal of the top of the can adjacent the edge. With the tool in this position the upper end of the guiding member C will engage underneath the edge of the flange, and form a fulcrum about which an up and down movement of the blade may be effected. This prevents the blade from slipping when making the cut around the edge to remove the top. If it be desired to cut along the side wall of the can adjacent the flange, the guiding member will engage the top or bottom wall, as the case may be.

A most effective and cheap way of constructing the can opener, above described, is from a blank illustrated in Fig. 4. As shown, the lower angular portion d of the

blank is bent upwardly on a line parallel with the lower line a² of the shank portion A, and back close against the front face of said portion A. This forms the guiding member. The upper angular portion d' is then bent downwardly at an angle, as indicated by the dotted line d², but away from the front face of portion A, to form the blade. The front edge of the blade will have been sharpened previously in any preferred way.

In the modification illustrated in Figs. 6 and 7, the shank A is curved downwardly at A' and the end of the downwardly curved portion is formed with an arcuate cutting edge E. The guiding member F is movably mounted on the rear face of the shank A adjacent the edge E, by a stud f. Said guiding member is provided with a recess f' to permit the necessary clearance of the blade at the edge of the can, and with a lug f² formed at the upper end of the guiding member to fit beneath the flange at the edge of a can. The lower end of the guiding member is provided with a stop f³ for limiting the movement of the guiding member. The entire shank and blade moves about the guiding member when making the cut in the top of a can.

What is claimed is:

1. A can opener, including, in combination, a shank, a blade carried by said shank and spaced therefrom, said blade having a forward cutting edge inclined relatively to the longitudinal axis of the shank, and a guiding projection formed on the shank in a plane parallel with and in front of the blade and with the rear edge of said projection inclined in the same general direction as the cutting edge, the outer face of said projection located between the blade and the shank and adapted to lie on the outside of a can, and the top of the projection positioned to engage underneath the flange joining the top and side walls of the can, substantially as described.

2. A can opener, including, in combination, a flat shank, a blade formed by an angular portion of said shank bent at an angle over the top edge of the latter and the blade lying in a plane spaced from and parallel with the plane of the shank, and a guiding projection formed by another angular portion of the shank bent upwardly from the bottom edge of the shank and lying close against the front face of the latter, said projection positioned in front of the blade and shaped to engage underneath the flange joining the top and side walls of a can, substantially as described.

3. A can opener including in combination a shank, a blade carried by said shank spaced therefrom and lying substantially parallel therewith with its cutting edge inclined forwardly toward the top of the blade, a guid-

ing member projecting from the side of the shank facing the blade with its rear edge inclined toward the top substantially parallel with the cutting edges of the blade, the front 5 face of the guiding member being positioned behind the rear face of the blade to permit the blade to clear the top edge of the can, said guiding member adapted to lie against the side wall of the can and engage beneath 10 the flange thereof.

4. As a new article of manufacture, a can

opener formed from a metal blank embodying a shank, a guiding member formed by bending up an angular portion as d on a line parallel with the lower line of the shank 15 and back against the front face of said shank, and a blade formed by bending an angular portion as d' downwardly at an angle but away from the front face of the shank.
